UNITED STATES PATENT OFFICE.

LUKE WHALLEY, OF WATERTOWN, NEW YORK.

CIRCULATING-BOX FOR PULP-SCREENS.

SPECIFICATION forming part of Letters Patent No. 694,707, dated March 4, 1902.

Application filed August 7, 1901. Serial No. 71,262. (No model.)

To all whom it may concern:

Be it known that I, LUKE WHALLEY, a citizen of the United States of America, residing at Watertown, in the county of Jefferson and State of New York, have invented a new and useful Improvement in Circulating-Boxes for Paper-Making Machines, of which the following is a specification.

My invention relates to an improvement in circulating-boxes for paper-making machines, the present improvement being an attachment for the screen.

As screens are now constructed they leave the "stuff," as it is termed, in such condition that slugs form and spoil the paper. The present invention is intended to prevent this waste of material and affords an effectual "wash-up" for the screens and practically does away with the slugs, resulting in a large saving in time and material. My improved circulating-box also lessens the water in the top of the screen, causes a transfer of the water back through the box, and mixes the material up beneath the screen, thus stopping all slugs, which is the cause of breaks on the machine and makes bad paper.

With the foregoing objects in view my invention consists in certain novel features of construction and combinations of parts, which will be hereinafter described, and pointed out in the claims.

In the accompanying drawings, Figure 1 is a plan view of a screen, showing my improved circulating-box in position alongside and in communication therewith. Fig. 2 is an end elevation, and Fig. 3 is a view in perspective, of my improved circulating-box.

A represents the framework of the machine, and B is the usual screen. C indicates my improved circulating-box. Of course its dimensions may be varied without limit; but the preferred dimensions from actual practical demonstration are about seven feet ten inches in length by, say, ten and three-fourths inches in height and seven and one-fourth inches in width or thereabout. As shown in Figs. 1 and 2, this box extends

along one side of the screen, where it is secured in any approved manner and with which it communicates freely through connecting-pipes 111. A pipe D extends lengthwise through the box, as illustrated, from one end to the other. Fresh water is admitted through the right-hand end of this pipe under a pressure of, say, forty pounds to the square inch through valve 2. This water discharges into the box, through holes 3, 3, bored at intervals in the portion of the pipe in the box, at say intervals of six inches apart. In this way the water is discharged evenly in the box. The valve 4 on the left is for the return of water. In this way the flow is kept up and a constant circulation is maintained, thus effectually regulating the stuff and preventing slugs. The pipe also serves to wash the screen when the machine is down and being cleaned, in that way saving the time of two men raising the screen and washing out with the hose.

It is evident that slight changes might be resorted to in the form and arrangement of the several parts described without departing from the spirit and scope of my invention, and hence I do not wish to limit myself to exact construction herein set forth; but,

Having fully described my invention, what I claim as new, and desire to secure by Letters Patent, is—

1. The combination with a screen for paper-making machines, of a circulating-box in communication therewith, a perforated pipe leading through said box, and valves in said pipe.
2. A circulating-box for paper-making screens, having a pipe extending therethrough, said pipe perforated for the discharge and distribution of its water throughout the interior of the box, and valves in each end of the pipe.

In testimony whereof I have signed this specification in the presence of two subscribing witnesses.

LUKE WHALLEY.
